Primary Examiner — Mary Ann Calabrese*Assistant Examiner* — Natalya M Rapundalo*(74) Attorney, Agent, or Firm* — Hubbard Law, PLLC;
Marc A. Hubbard(57) **CLAIM**

The ornamental design for a drawer organizer, as shown and described.

DESCRIPTION

FIG. 1 is a front perspective view of a drawer organizer; FIG. 2 is a front elevation view thereof; FIG. 3 is a rear elevation view thereof; FIG. 4 is a top plan view thereof; FIG. 5 is a bottom plan view thereof; FIG. 6 is a right side view thereof; and, FIG. 7 is a left side view thereof.

The broken lines shown in the drawings illustrate portions of the drawer organizer and form no part of the claimed design. The drawer organizer is shown with a symbolic break in its length. The appearance of any portion of the article between the break lines forms no part of the claimed design.

1 Claim, 5 Drawing Sheets(56)
